UNITED STATES PATENT OFFICE.

JOHN H. RICHARDSON, OF MELROSE, AND ALBERT E. HUDSON, OF BEVERLY, MASSACHUSETTS, ASSIGNORS TO UNITED SHOE MACHINERY CORPORATION, OF PATERSON, NEW JERSEY, A CORPORATION OF NEW JERSEY.

RELASTING MACHINE.

Application filed July 9, 1919. Serial No. 309,555.

This invention relates to machines generally known as relasting machines, for use in inserting lasts in shoes. Such machines are of particular utility in the manufacture 5 of turn shoes having nailed heel seats, and the invention is accordingly illustrated and described herein with reference to such use; but it should be understood that the invention is not thus limited in its applicability, 10 since a machine in which many of the novel features of the invention are embodied may be used with advantage for inserting lasts in shoes of other types.

An object of the invention is to provide 15 a machine of improved construction by the use of which a shoe may be mounted on a last in an expeditious and effective manner with comparatively little effort upon the part of the operator and without injury 20 either to the shoe or to the last. Features of the invention consist in means for vibrating a shoe together with novel means for drawing the forward portion of a shoe on to a last as the shoe is vibrated. In the 25 construction illustrated this feature is embodied in a support for the toe of the shoe and a gripper for the heel portion of the sole, the two being moved together toward the last by a single operating lever, and the 30 movement of the toe support throwing into operation a clutch which controls mechanism for vibrating the support for the toe of the shoe.

A further feature of the invention consists 35 in the provision of novel means for drawing the heel portion of the partially inserted shoe on to the last. The construction shown embodies a gripping member having two jaws, an inner shoe-horn shaped member and 40 an outer co-operating member, which may be operated to grip the heel portion of the upper of the shoe and draw it on to the last. Provision is also made for vibrating the last while the heel portion of the shoe is being 45 drawn thereon, to settle the shoe on the last. Another feature of the invention consists 50 in the provision of means to beat or pound the shank and other portions of the sole, while the heel portion is being settled on to the last, and thereafter, to shape the shank and other portions of the sole to the last.

The above and other features of the inven-

tion, including certain details of construction and combinations of parts, will now be described with reference to the accompanying drawings and pointed out in the claims. 55

Referring to the drawings,

Fig. 1 is a side elevation of a relasting and leveling machine with parts of the machine in section and showing the last support in 60 the position it occupies while the forward part of the shoe is being pulled thereon;

Fig. 2 is a side elevation of the beater mechanism and the last support showing the latter in the position it occupies while the 65 heel portion of the shoe is being pulled thereon;

Fig. 3 is a somewhat diagrammatic cross-section on the line 3—3 of Fig. 1 showing certain clutch controlling mechanism; and 70

Fig. 4 is a section on line 4—4 in Fig. 2.

In the drawings 10 denotes the main frame having a forwardly and upwardly extending portion 12. To the base of the main frame there is pivoted for universal motion at 14, 75 15 a post 16 to the top of which is hinged at 18 a last support 20 having a slidable pin 22 mounted therein to receive the last 24. Near the upper end of the post 16 is mounted a fork 26 to receive and support the heel 80 end face of the last when positioned as indicated in Fig. 1. To hold the post 16 in fixed position while the forward portion of the shoe is being pulled on to the last there is provided a latch 28 provided with a pin hav- 85

ing a tapered upper end 30 adapted to seat itself in a correspondingly shaped socket in arm 32 of the main frame. A spring 34 tends to thrust pin 30 into its socket from which it may be withdrawn by suitable 90 mechanism, which, as exemplified in the drawings, consists of a pin 38 mounted in the lower end of the latch member and adapted to withdraw the same upon the operation of treadle 36. Pivoted to this treadle is a hook 95 member 42 adapted to engage a pin 44 mounted in the main frame to hold the latch in its disengaged position. The upper end of this hook may be enlarged to provide a surface adapted to be engaged by the toe 100 of the operator to release the hook whereupon the treadle may be raised and the latch member 30 seated.

Turning now to the means for seating the

last in the forward portion of the shoe, there is provided a support 50 for the sole at the toe of the shoe carrying two blocks 52 of rubber or other suitable material to engage 5 and grip the sides of the toe portion of the shoe. This support 50 is pivoted at 54 to a rod 56 yielding held by spring 58 in a sleeve 60 at the lower end of which is formed a yoke 62 pivotally mounted on the 10 main drive shaft 100. A roll 64 is provided at the lower end of rod 56 and is held by spring 58 against a cam 66 so that upon rotation of the cam by means presently to be described the support 50 will be rapidly 15 vibrated.

Pivoted to the sleeve 60 is an extensible link 67 provided with a compression spring 68 to yieldingly connect the toe support 50 with a gripper 70 pivoted to the main frame 20 at 72 and provided with jaws 74 and 76 adapted to grip the heel portion of the sole of the shoe. Pivoted to the base of the main frame of the machine at 78 is a treadle 80 made in the form of a bell-crank lever and pivoted at its upper portion 82 to a link 86, the latter being pivoted at 88 to one end of a U-shaped lever 90 pivoted at 92 to the main frame. The U-shaped lever 90 is pivoted at 93 to one end of a link 94 the other end of 25 which is pivoted to the downwardly extending end of the pivoted jaw 76 of the gripper. The treadle 80 is normally held in its raised or inoperative position by means of a spring 96 connecting it with the main 30 frame.

While the machine is at rest the support for the forepart of the shoe and the grippers occupy substantially the position indicated in dotted lines in Fig. 1. A last having 40 been placed on the pin 22, and occupying the position indicated in Fig. 1, the shoe is placed with the forepart of its sole on the toe support and the rear portion of the sole between the jaws of the gripper. The depression of treadle 80 operates first to close the jaws of the gripper upon the sole of the shoe and then to swing the gripper downwardly and to the right, as viewed in Fig. 45 1. This downward swinging movement of the gripper is transmitted by the link 67 to the toe support, the two co-operating to pull the shoe on to the last. The movement of the yoke 62 of the toe support about shaft 100 operates as will now be described, to 50 throw in clutch mechanism which causes cam 66 to vibrate the forward portion of the shoe to settle the same on the last.

Mounted on the main drive shaft 100 is a belt pulley 102 about which passes a belt 60 104 driven from any suitable source of power. Connected to shaft 100 is a pulley having grooves to receive belts 106 and 108 which drive other operating parts of the machine presently to be described. On the 65 depending portion of one of the arms of

yoke 62 (see Fig. 3) is an inclined or wedge surface 112 adapted upon the swinging of 60 to co-operate with a corresponding wedge surface 114 formed on a sleeve 116 rigidly mounted on pin 118. This pin 118 is 70 mounted for longitudinal movement in the main frame and is moved in the direction of wedge surface 112 by a compression spring 120. Yoke 121 formed on sleeve 116 operates to control a clutch member 122 to 75 move the same towards and away from co-operating clutch member 124 formed integral with cam 66. It will thus be seen that the movement of the toe support from dotted to solid line positions in Fig. 1 will operate 80 to permit sleeve 116 to be slid to the left as viewed in Fig. 3 under the action of spring 120 to throw clutch 122, 124 into operation and consequently to vibrate rod 56 and the 85 toe support.

After the last has been inserted in the forepart of the shoe the last support is swung upwardly by the operative about pivot 18 to invert the same and the last is then rotated in a horizontal plane through 90 180° to position it as indicated in Fig. 2.

Pivoted to the base of the main frame of the machine is a third treadle 130 to which is connected a rod 132. Supported at the upper end of this rod is a shoe horn comprising a pair of co-operating jaws 134 and 136 for gripping and pulling the shoe downwardly on to the last. The gripping portion of jaw 134, as indicated, is of more or less conventional shoe horn shape and is adapted 100 to be inserted inside of the shoe and to be pulled down between the upper and the last. Jaw 136, which may be a block of rubber or other suitable material, is pivoted to bell-crank lever 138 which latter is pivoted at 140 to the extremity of a handle portion 142 of the shoe horn. The other arm of bell-crank lever 138 is pivoted to the extremity of rod 132 which latter passes through an opening in an extension of the lower end of 110 the shoe horn. Rigid with the post 16 is an outstanding arm 144 provided with an elongated slot to movably hold the rod 132 in 115 position.

Journaled in the post 16 is a shaft 150 on which is mounted clutch mechanism similar in all its essential characteristics to that of Fig. 3, and adapted to be thrown into and out of operation by the movement of an arm 152 through which passes rod 132, arm 152 being moved into and out of clutch engaging positions by means of collars 154 and 156 rigidly but adjustably mounted on the rod 132. A downwardly extending portion of arm 152 carries a wedge surface, a movement 120 of which towards and from operative position controls the operation of cam 158 in the manner explained in connection with Fig. 3. Engaging the cam 158 is a roll 125 160 mounted on a downwardly extending 130

yoke portion 162 of rod 164, this latter being mounted for longitudinal vibrating movement in post 16. To hold roll 160 in engagement with cam 158 there is provided a spring 170 connected at one end to an eye 171 formed on yoke 162 and at its other end to post 16 at 172. The upper end of rod 164 contacts with the lower end of pin 22, when in the position indicated in Fig. 2, to vibrate the last in a direction transverse to the plane of the sole thereof to assist in settling the shoe on the last as the heel portion of the upper is drawn into position by the shoe horn.

15 To assist in settling the shoe on the last and to shape the sole thereto there is provided a beater which may be thrown into and out of operation by means of a handle 180 pivoted at 197 to the upper portion of 20 the main frame and adapted to be locked in operative position by means of a sliding pin 182, controlled by a pivoted lever 183, held in operative position by spring 185, as clearly shown in Figs. 2 and 4. This beater comprises a rod 184 slidably mounted in a sleeve 186 and having a beating head 188 connected by a ball and socket joint 190 to its lower end. Spring 192 connected to rod 184 and sleeve 186 of the beater normally tends to hold the beater in its lowermost position. Clutch mechanism similar to that of Fig. 3 is provided for controlling the operation of the beater so that the same will be vibrated when moved into the position of Fig. 2, but when 30 the handle 180 is elevated, as indicated in Fig. 1, will come to rest. For this purpose handle 180 is provided with a wedge surface 194 co-operating with a wedge surface 196 of a clutch shifting yoke, the two controlling 35 the operation of a clutch mounted on shaft 197, in the manner described in connection with Fig. 3. Mounted on shaft 197 and controlled by this clutch is a cam 200 co-operating with a roll 202 for reciprocating the beater. Roll 202 is mounted on a link 204 shown in dotted lines in Figs. 1 and 2 and in cross-section in Fig. 4 pivoted at one end to the handle 180 at 181 and pivoted at the other end, as at 205, to the lower end 40 of link 206. The upper end of link 206 is pivotally connected to the stem 184 of the beater. The sleeve 186 of the beater is pivoted at 208 to projection 210 of the handle 180 and is also pivoted at its upper end to 45 a link 212 connecting it with the forward portion of the main frame of the machine. It will thus be seen that the rotation of cam 200 will rock lever 204 about its fulcrum 181 and will thus reciprocate link 206 and 50 through it the beater.

In order to tension belt 106 to the desired extent irrespective of the position of post 16 a suitable belt tightener, indicated at 214, is provided.

While it is believed that the mode of operation of the machine will be clear from the above description it may, for purposes of convenience, be recapitulated as follows:

A last having been placed on pin 22 and the same moved to the position of Fig. 1, the forepart of the shoe is placed thereover so far as convenient by hand, at this time the toe support and the grippers for the heel portion of the sole occupy substantially the positions shown in dotted lines in Fig. 1. The operative thereon presses downwardly upon treadle 80 which first closes the jaws of the gripper 70 upon the heel portion of the sole of the shoe and thereafter moves the gripper and the toe support 50 rearwardly and downwardly to the full line position of Fig. 1, thus seating the last in the forepart of the shoe. As the support 50 is thus moved, cam 66 is operated to vibrate the toe support and the shoe to settle the last in the shoe. Treadle 80 is now released whereupon spring 96 moves the gripper 70 and the toe support 50 back to the dotted line position of Fig. 1, leaving the last inserted in the forepart of the shoe. Handle 180 and the beater being in their elevated or inoperative position, the last is now swung forwardly and rotated horizontally through 180° to the position of Fig. 2. The shoe horn is now manipulated by means of the handle portion 142 to grip the rear portion of the upper of the shoe which has now to be pulled down into place. By means of treadle 130 the operative pulls the rear portion of the upper held by the shoe horn down into place and at the same time the last is vibrated through rod 164, cam 158 and their actuating mechanism. During these operations post 16 is, of course, rigidly held in position by its latch mechanism. When the last is nearly or completely inserted in the shoe the operative pulls down on handle 180 latching the same in the position of Fig. 2, whereupon beater 188 is vibrated to settle the shoe on the last. At this stage of the operation by pressing downward on treadle 36 the operative releases the latch of post 16 and thereafter moves the post from one position to another in order that the beater may shape and mold various portions of the sole of the shoe as may be necessary. The handle portion 142 of the shoe horn at this stage of the operation forms a convenient means by which the operative may swing the post from one position to another.

The above described beating mechanism is not claimed herein, as it forms the subject-matter of our divisional application No. 603,821, filed Nov. 28, 1922. Other features of novelty not claimed herein, relating to the means for supporting and for vibrating the last, are claimed in our application Serial No. 251,433, filed Feb. 2, 1923, which

application is a division of our above-mentioned divisional application No. 603,821.

Having described our invention, what we claim as new and desire to secure by Letters 5 Patent of the United States is:

1. A machine of the class described having, in combination, means for supporting the forepart of a shoe, means for gripping the heel portion of the sole of a shoe, and 10 means for moving the supporting and the gripping means to force a last into the forepart of the shoe while so held.

2. A machine of the class described having, in combination, a last supporting member, means for supporting the forepart of a shoe, means for gripping the heel portion 15 of the sole of the shoe, and means for simultaneously moving the forepart supporting and the gripping means towards a last on 20 the last supporting member, to thrust the forepart of the shoe on to the last.

3. A machine of the class described having, in combination, means for simultaneously gripping the heel end of the sole and 25 engaging the forepart of a shoe, a support for a last to be inserted in the shoe, and means for relatively moving said means and the last, to thrust the last into the shoe.

4. A machine of the class described having, in combination, means for supporting the forepart of a shoe, means for gripping the heel portion of the sole of the shoe, a last support, means for simultaneously moving said forepart support and said gripping 35 means towards a last on the last support to thrust the shoe on to the last, and means for vibrating said forepart support as the shoe is thrust on to the last.

5. A machine of the class described having, in combination, means for supporting the forepart of a shoe, means for gripping the heel portion of the sole of the shoe, a last support, means for simultaneously moving said forepart support and said gripping 45 means towards a last on the last support to thrust the shoe on to the last, and means for vibrating the shoe in a direction transverse to the plane of the sole thereof.

6. A machine of the class described having, in combination, means for gripping the heel portion of the sole of a shoe, means for forcing a last into the forepart of the shoe, and means for vibrating the shoe while the last is being forced into the shoe.

55 7. A machine of the class described having, in combination, a last supporting member, means for supporting the forepart of a shoe, means for gripping the heel portion of the sole of the shoe, means for simultaneously 60 vibrating the forepart of the shoe and moving the forepart support and the gripping means towards a last on the last supporting member to thrust the shoe on to the last.

8. A machine of the class described having, in combination, devices for simultaneously gripping the heel end of the sole and engaging the forward portion of a shoe, a support for a last to be inserted in the shoe, means for vibrating the shoe, and means for relatively moving said devices and the last to thrust the last into the shoe. 65

9. A machine of the class described having, in combination, a last supporting member, means for supporting the toe of a shoe, means for gripping the heel portion of the sole of the shoe, and means for vibrating the toe support while the toe support and the gripping means thrust the shoe on to the last. 75

10. A machine of the class described having, in combination, a support for the forward portion of a shoe, means for gripping the heel portion of the sole of a shoe, and means for simultaneously moving said support and said gripping means in a direction lengthwise of the shoe to pull the same on to a last. 80

11. A machine of the class described having, in combination, a last support, means for supporting the forward portion of a shoe, means for gripping the heel portion of the sole of the shoe, means for simultaneously moving said forepart supporting means and said gripping means lengthwise of the shoe to pull the forepart of the shoe on to a last mounted on the last support, and means to vibrate the support for the forepart of the shoe to settle the shoe on the last. 90

12. A machine of the class described having, in combination, a last support, means for supporting the forepart of a shoe, means for gripping the heel portion of the sole of the shoe, means for simultaneously moving said forepart supporting means and said gripping means lengthwise of the shoe to pull the same on to a last mounted on the last support, and a cam to vibrate the support for the forepart of the shoe. 95

13. A machine of the class described having, in combination, an invertible last support, means for forcing the forward portion of a shoe on to a last held on the support, and means for gripping the heel portion of the upper of the shoe construction and arranged to pull the heel portion on the last after the last has been inverted. 110

14. A machine of the class described having, in combination, a last support, means for forcing the forepart of a shoe on to a last held on the support, means to pull the heel portion of the shoe on to the last, and means operating through the last support to vibrate the last while the heel portion of the shoe is being pulled thereon. 120

15. A machine of the class described having, in combination, a last support, means

for forcing the forepart of a shoe on to a last held on the support, means to pull the heel portion of the shoe on to the last, and means to vibrate the last in a direction transverse to the plane of the sole thereof while the heel portion of the shoe is being pulled thereon.

16. A machine of the class described having, in combination, an invertible last support, means for forcing the forepart of a shoe on to a last held on the support, and means to pull the heel portion of the shoe on to the last after the inversion thereof.

17. A machine of the class described having, in combination, an invertible last support, means for forcing the forepart of a shoe on to a last held on the support, means constructed and arranged to pull the heel portion of the shoe on to the last after the inversion of the last support, and means to vibrate the last while the heel portion of the shoe is being pulled thereon.

18. A machine of the class described having, in combination, an invertible last support, means for forcing the forepart of a shoe on to a last held on the support means for vibrating the forepart of the shoe while it is being forced on to the last support, means constructed and arranged to pull the heel portion of the shoe on to the last after the inversion of the last support, and means to vibrate the last while the heel portion of the shoe is being pulled thereon.

19. A machine of the class described having, in combination, an invertible last support, means for forcing the forepart of the shoe on to a last held on the support, means constructed and arranged to grip the heel portion of the upper of the shoe after the last has been inverted to pull the heel portion on to the last, and means for vibrating the last while the heel portion is being pulled thereon.

20. A machine of the class described having, in combination, a last support, means for forcing the forepart of a shoe on to a last held on the support, means constructed and arranged to grip the heel portion of the upper of the shoe to pull the heel portion on to the last, and means for vibrating the last in a direction transverse to the plane of the sole of the shoe.

21. A machine of the class described having, in combination, means for forcing the forepart of a shoe on to a last, means constructed and arranged to grip the heel portion of the upper of the shoe to pull the heel portion on to the last, and means to vibrate the last in a direction transverse to the plane of the sole of the shoe.

22. A machine of the class described having, in combination, a last support, gripping means of yielding material for engaging the forepart of a shoe and forcing it on to a last held on the support, and co-operating jaws

constructed and arranged to grip the heel portion of the upper of the shoe and movable to draw it on to the last.

23. A machine of the class described having, in combination, a last support, means for forcing the forepart of a shoe on to a last held on the support, a shoe horn constructed and arranged to grip the heel portion of the upper of the shoe and draw it on to the last and means acting directly upon the heel end of the last to vibrate the last while the shoe is being drawn thereon.

24. A machine of the class described having, in combination, a last support, means for forcing the forepart of a shoe on to a last held on the support, a shoe horn constructed and arranged to grip the heel portion of the shoe and draw it one to the last, and means to vibrate the last in a direction transverse to the plane of the sole while the shoe is being drawn thereon.

25. A machine of the class described having, in combination, a last support, means for pulling the heel portion of a shoe on to a last supported thereby, and mechanism rendered operative by movement of said means for vibrating the last while the heel portion of the shoe is being pulled thereon.

26. A machine of the class described having, in combination, a last support, means for pulling the heel portion of a shoe on to a last supported thereby, and means for vibrating the last in a direction transverse to the plane of the sole thereof while the heel portion of the shoe is being pulled thereon.

27. A machine of the class described having, in combination, a pivoted post, a last support mounted thereon, a latch mechanism operable to hold the post in fixed position, means to vibrate the last, and means to grip the heel portion of the upper of the shoe to pull it on to the last.

28. A machine of the class described having, in combination, a last engaging member, a shoe horn for pulling the heel portion of a shoe on to a last supported thereby, and means for vibrating the last in a direction transverse to the plane of the sole of the shoe while the shoe is being pulled on to the last.

29. A machine of the class described having, in combination, a last support, a shoe horn for pulling the heel portion of a shoe on to a last supported thereby, said shoe horn having a pair of relatively movable jaws constructed and arranged to grip the heel portion of the upper of the shoe while it is being pulled on to the last, and means for vibrating the last while the heel portion of the shoe is being pulled thereon.

30. A machine of the class described having, in combination, a last support, a shoe horn for pulling the heel portion of a shoe on to a last supported thereby, said shoe horn having a pair of relatively movable

- jaws constructed and arranged to grip the heel portion of the upper of the shoe while it is being pulled on to the last, and means for vibrating the last in a direction transverse to the plane of the sole while the heel portion of the shoe is being pulled thereon. 5 a shoe, a support for a last to be inserted in the shoe, means for relatively moving the gripping means and the last, to thrust the last into the shoe, and auxiliary means set in operation by said relative movement and acting to increase the force acting to effect said movement. 70
31. A machine of the class described having, in combination, a last support, means for pulling the heel portion of a shoe on to a last supported thereby, and means to beat the sole of the shoe. 32. A machine of the class described having, in combination, a last support, means for pulling the heel portion of a shoe on to a last supported thereby, means for vibrating the last while the heel portion of the shoe is being pulled thereon, and means to beat the sole of the shoe. 15 75
33. A machine of the class described having, in combination, a last support, means for pulling the heel portion of a shoe on to a last supported thereby, means for vibrating the last in a direction transverse to the plane of the sole thereof while the heel portion of the shoe is being pulled thereon, and means to beat the sole of the shoe. 20 80
34. A machine of the class described having, in combination, a last support, a shoe horn for pulling the heel portion of a shoe on to a last supported thereby, means for vibrating the last in a direction transverse to the plane of the sole while the shoe is being pulled on to the last, and means for beating the sole of the shoe. 30 85
35. A machine of the class described having, in combination, a last support, means for forcing the forward portion of a shoe on to a last held on the support, means constructed and arranged to grip the heel portion of the upper of the shoe to pull the heel portion on to the last, and means for beating the sole of the shoe. 35 90
36. A machine of the class described having, in combination, a last support, means for forcing the forward portion of a shoe on to a last held on the support, means constructed and arranged to grip the heel portion of the upper of the shoe to pull the heel portion on to the last, means for vibrating the last while the heel portion is being pulled thereon, and means for beating the sole of the shoe. 40 95
37. A machine of the class described having, in combination, means for supporting the forepart of a shoe, means for gripping the heel portion of the sole of a shoe, means for forcing a last into the forepart of the shoe while so held, and auxiliary means set in operation by the forcing of the last into the forepart of the shoe and operative to increase the effectiveness of the force acting to seat the last in the shoe. 45 100
38. A machine of the class described having, in combination, means for gripping the heel end of the sole and the forepart of 50 105
41. A machine of the class described having, in combination, a last support, means for forcing the forepart of a shoe on to a last held on the support, means to pull the heel portion of the shoe on to the last, and means to vibrate the last while the heel portion of the shoe is being pulled thereon, said vibrating means being constructed and arranged to be set in operation by the actuation of said heel-pulling means. 55 110
42. A machine of the class described having, in combination, an invertible last support, means for forcing the forepart of a shoe on to a last held on the support, auxiliary means set in operation by the actuation of said forcing means and effective to increase the force applied thereby, means to pull the heel portion of the shoe on to the last after the inversion thereof, and auxiliary means set in operation by the actuation of said heel-pulling means and effective to assist in the pulling action. 60 115
43. A machine of the class described having, in combination, a last support, means for pulling the heel portion of a shoe on to a last supported thereby, and means for vibrating the last while the heel portion of the shoe is being pulled thereon, said vibrating means being constructed and arranged to be set in operation by the movement of the heel-pulling means. 65 120
44. A machine of the class described having, in combination, a pivoted post, a last support mounted thereon, a latch for holding the post in fixed position, means for beating the sole on a shoe mounted on a last 125 130

- held by the last support, to settle the shoe on the last, and a handle arranged to lower the sole beating means against the shoe, said beating means being constructed to be set in operation by the lowering of the handle. 45. A machine of the class described having, in combination, a last support, means for pulling the heel portion of a shoe on to a last supported thereby, auxiliary means set in operation by the actuation of the heel-pulling means, and assisting in the pulling of the shoe on the last, and means to beat the sole of the shoe. 46. A machine of the class described having, in combination, a mechanism for operating on a shoe, and an auxiliary mechanism effective to assist the first named mechanism and set in operation by the actuation thereof. 47. In a relasting machine, in combination, a shoe horn movable in a direction to draw the counter portion of a shoe on a last, and a member progressively to apply pressure to the bottom of the shoe, to force it against the last after the counter portion of the shoe has been drawn over the last. 48. In a shoe machine, in combination, a last support, means co-operating with the last support to relast a shoe, and means to level the sole of the relasted shoe, said last support being movable to enable the leveling pressure to be applied progressively along the sole. 49. In a relasting machine, an element movable in a direction to draw the counter portion of a shoe on a last, and a power-actuated member for applying pressure to the shoe bottom to co-operate with said element in seating the counter portion of the shoe on the last. 50. In a relasting machine, members arranged to engage the upper and support the sole at the toe portion of a shoe on a last, means for vibrating said members to seat said toe portion of the shoe, and power-actuated means operable after the toe portion has been seated thereby to seat the counter portion of the shoe on the last. 51. In a relasting machine, in combination, a device to engage the upper and tread face of the sole at the toe portion of a shoe on a last, means for vibrating said device, treadle-controlled mechanism to actuate said means, means thereafter operable to seize the counter portion of the shoe and to seat it on the last, and separate treadle-controlled mechanism for actuating said second means. 52. In a relasting machine, in combination, means to settle the toe portion of a shoe on a last by successive pressure impulses applied to the tread face of the sole, a support to hold the last stationary during the seating of the toe portion of the shoe thereon, and a gripper device movable after the seating of the toe portion to seize the counter portion of the shoe and to seat it on the last, said support being arranged to hold the last stationary during the seating of the counter portion of the shoe thereon. 53. In a relasting machine, in combination, a support for a last and shoe, a horn movable in a direction to draw the counter portion of a shoe on a last supported thereby, treadle-controlled mechanism for moving said horn, movable means for engaging the shoe bottom, and mechanism for positively actuating said means simultaneously to apply pressure to the shoe bottom to co-operate with said horn in seating the counter portion of the shoe on the last. 54. In a relasting machine, in combination, means operable in seating the counter portion of a shoe on a last, an independent device to co-operate therewith in seating said counter portion, and mechanism for operating said device and said means simultaneously. 55. In a relasting machine, in combination, a member movable in a direction to seat the counter portion of a shoe on a last, a movable pressure device to act on the shoe bottom, and operator-controlled means for actuating said pressure device. 56. A relasting machine comprising, in combination, a support for a last, means for seating the toe portion of a shoe on a last supported thereby, a pair of jaws to engage respectively the inside and the outside of the counter portion of the shoe, means first to close the jaws and then to move them to draw the counter portion of the shoe on the last, and means movable over the sole of the shoe for shaping the sole to the last. 57. A relasting machine comprising, in combination, a jack-pin for holding a last, power-operated means continuously under the control of the operator for seating the toe portion of a shoe on a last supported thereby, a pair of jaws to engage respectively the inside and the outside of the counter portion of the shoe, and means first to close the jaws and then to move them to draw the counter portion of the shoe on the last. 58. A relasting machine comprising, in combination, a jack-pin for holding a last, means including a member engaging forwardly of the shank a shoe on a last held stationary thereby, for seating the toe portion of the shoe on the last, and a gripper device operated after the seating of the toe portion of the shoe on the last to seize the counter portion of the shoe and draw it on the last, and means for pressing the shoe bottom against the last, the jack-pin being movable to transfer the shoe from the field of operations of said toe seating means to the field of operations of said pressing means. 59. A machine of the class described having, in combination, means for supporting a

last, means to grip and pull rearwardly the heel end of the sole of a shoe mounted on the last, and means engaging the toe part of the sole of the shoe for forcing the shoe on the last.

60. In a machine of the class described, the combination with a last support and means to grip the heel end of the sole of a shoe mounted on the last of movable means to engage the toe part of the shoe for assisting the gripping means in forcing the shoe on the last.

61. A machine of the class described having, in combination, a support for a last, a device for gripping the heel end of the sole of a shoe mounted on the last, means for moving the device in a direction to pull the shoe on the last, and means movable rela-

tively to said last support and engaging the toe part of the shoe mounted on the last to assist the gripping device in forcing the shoe on the last.

62. A machine of the class described having, in combination, means for supporting a last, a device for seizing the heel end of the sole of a shoe mounted on the last, means for moving said device in a curved path to draw the shoe on the forepart of the last, and means movable relatively to said last support for engaging the toe part of the sole of the shoe to assist the heel-seizing device in drawing the shoe on the forepart of the last.

In testimony whereof we have signed our names to this specification.

JOHN H. RICHARDSON.
ALBERT E. HUDSON.
